RAILWAY TRACK TORPEDO

George B. Jackson, Orlando, Fla.

Application August 27, 1938, Serial No. 227,173

2 Claims. (Cl. 246—487)

This invention relates to improvements in railway track torpedoes, and more particularly to torpedoes of the type employing a metallic envelope or container which functions both to hold the explosive and as a means for securing the torpedo to the track.

A principal object of the invention is to provide a torpedo of this type, wherein the envelope or container consisting of an integral sheet of metal, preferably lead foil, shall have in that portion immediately embracing the explosive composition, or at least at the top and sides of this portion, a wall thickness not exceeding a permissible maximum, and shall exhibit in the end portions thereof, which constitute the straps for securing the torpedo to the rail, a greater thickness of metal conforming at least to a permissible minimum for these portions.

More specifically, the invention contemplates the provision of a tubular metallic container consisting of an integral sheet of lead foil or other suitable sheet metal, which by reason of the novel formation hereinafter described shall conform accurately to the controlling specifications for standard track torpedoes.

The invention will be more readily understood by reference to the attached drawings, wherein:

Figure 1 is an enlarged view in perspective of a torpedo made in accordance with my invention;

Figs. 2 and 3 are, respectively, views in perspective of the two principal component parts of the torpedo;

Figs. 4, 5 and 6 are, respectively, enlarged transverse sectional views showing successive steps in the formation of the torpedo, said sections being taken on a line corresponding to line 6—6, Fig. 1;

Fig. 7 is a view in perspective of an element of the torpedo shown in the preceding figures;

Fig. 8 is a section on the line 8—8, Fig. 1;

Fig. 9 is a view in perspective of a torpedo constituting another embodiment of the invention;

Fig. 10 is a section on the line 10—10, Fig. 9;

Fig. 11 is a section on the line 11—11, Fig. 9, and

Fig. 12 is a view in perspective of an element of the torpedo shown in Fig. 9.

A torpedo made in accordance with my invention consists, in a preferred embodiment, of a body 1 of explosive composition protected by a suitable waterproof envelope, 2, of waxed paper or the like; the whole wrapped in a metallic container consisting of an integral sheet 3 of lead

foil or other suitable material. As shown in Fig. 3, the metal sheet 3 is considerably wider than the perimetral dimension of the explosive body 1 for a purpose hereinafter described, and is sufficiently greater in length than the cylinder 1 to afford at the ends of the latter extending portions of metal which function as straps for securing the torpedo to the rail.

In order to bring torpedoes of this type into conformity with the specifications of the American Railway Association for standard track torpedoes, it is necessary that the lead foil container 3 shall have in those portions embracing the top and sides of the body of explosive when the torpedo is properly secured to the rail a wall thickness not exceeding a predetermined maximum, so that the weight of metal in these parts shall not be great enough to cause injury by flying fragments when the torpedo is exploded. It

is further required that the strap-like ends of the 20 torpedo, if composed of lead, shall have a thickness consistent with the function of those parts to securely bind the torpedo on the rail. Heretofore in torpedoes of this type it has been found necessary to compromise between these two requirements. Thus, if for the conventional container a lead foil is employed of sufficient thickness to

afford an adequate weight and strength of metal in the strap portions of the torpedo, then the wall thickness of the container in that portion embracing the explosive body is greater than the considered safe maximum. If, on the other hand, the container is composed of foil sufficiently thin to insure against injury from flying fragments, then the strap portions of the container fail to

meet the specifications relating to adequate strength in those portions.

Specifically, the specifications of the A. R. A., above referred to, require that if the means for fastening the torpedo on the rail consists of 40 lead, it must take the form of "a pure lead strap five-sixteenths inch wide, seven and one-quarter inches long and four one-hundredths inch thick." A further requirement, as stated, is to the effect that the torpedo when exploded must cause no dangerous projection of fragments. In order to meet this latter requirement, it is desirable that the thickness of the lead foil used to form the envelope shall not exceed five one-thousandths inch, but if, in producing a torpedo in accordance with the prior practices, the explosive compound is inserted in a simple tube made of this gauge of foil, the projecting ends of the tube which are to function as the securing strap will fail to meet the weight and dimen-

sional requirements for that element. If, on the other hand, foil of a thickness sufficient to produce adequate weight in the strap portion be used, then the torpedo fails to meet the requirement relating to flying fragments.

In producing a torpedo in accordance with my invention, and for the reason set forth above, I employ, preferably a pure lead foil of no more than five one-thousandths of an inch in thickness. A sheet, 3, of this foil is used having a length somewhat in excess of seven and one-quarter inches (the required length of the strap, as set forth above), and having a width substantially in excess of that required to permit the forming of the sheet lengthwise into a tube of approximately one-half inch diameter. A tube of this size is adapted to contain the amount of explosive compound required by the specifications and to afford at the ends of the explosive body a sufficient length of metal to adequately secure the torpedo to the rail. When the sheet, 3, of foil is wrapped around the explosive 4, the excess width of the sheet is employed to form an interfolded seam of several thicknesses of foil, extending along one side of the tube and continuously from one end to the other, as indicated at 4 in Figs. 1, 6 and 8. As shown in the latter figure, this seam consists in the present instance of four layers of foil, and the excess width of the foil sheet which provides for the seam is such that the width of the latter is approximately, but not less than, five-sixteenths of an inch, or approximately 20% of the circumference of the tubular casing.

It will now be seen that if the extended ends 5 of the tube at opposite ends of the explosive body were pressed flat upon the seam, there would exist in those portions six thicknesses of foil, or an effective thickness of thirty-one thousandths of an inch. This is less than the minimum thickness of strap required by the specifications. The ends of the half-inch tube when flattened, however, would have a width considerably in excess of the required five-sixteenths inch strap, and this excess width is sufficient to permit the tucking in of the opposite sides of the tube, as indicated at 6, without, however, reducing the effective width below the required five-sixteenths of an inch minimum. When the tube is thus folded, the tucks 6 afford two additional thicknesses of the five one-thousandths inch foil, bringing the total thickness of the strap up to the required four one-hundredths of an inch. In this manner a strap is produced which meets the specifications in full degree both as to material and dimensions, and at the same time the thickness of foil at the top and sides of the explosive body does not exceed five one-thousandths of an inch.

The formation described above adapts itself well in other respects to the aforesaid standard specifications. The specifications require that the torpedo must withstand immersion in cold water for at least one hour without impairing its explosive properties. The lead sheath is in itself impermeable to water, but it is essential that the seam shall be of a character to exclude passage of water to the interior of the lead casing. The formation of an adequate securing strap, as described above, produces a seam of this character, and the interfolded layers of foil to which the seam is composed effectively precludes the entrance of moisture through the seam.

This character of interfolded seam has a further desirable feature. It is required by the spec-

ifications that the torpedo display conspicuously the word "Danger." While it is difficult to imprint this word upon the lead sheath itself, the seam formation provides a simple and highly effective means for securely attaching to the torpedo a suitable label bearing the necessary warning. One desirable method of forming the seam is illustrated in Figures 4, 5 and 6. Figure 4 shows the excess strips 7, 7 of the foil sheet extending away from their juncture in the cylinder 8. Figure 5 shows the initial joint folding on themselves of the strips 7, 7. Figure 6 shows the second and final fold which completes the seam and lays the latter flatly against the side of the cylinder 8. In securing the label to the torpedo as set forth above, it is only necessary, as shown in Fig. 4, to pass the label, which is indicated by the reference numeral 9, around the cylinder 8 and along the opposite faces of the foil strips 7. In the present instance, one end of the label is passed outwardly and around the outer extreme edges of the strips 7 as indicated at 11, whereas the opposite end of the label is terminated short of the outer end edges of the strips. The initial fold of the foil, as illustrated in Fig. 5, securely anchors the ends of the label in the seam, and in the final fold of the foil, as shown in Fig. 6, the label is clamped in place around the cylindrical portion of the torpedo in a manner preclusive of accidental removal.

While a foil of five one-thousandths of an inch thickness formed into a casing as described above avoids all danger from flying fragments of metal, a foil of smaller gauge may be used, if desired, without departing from the invention. It is to be noted that in the use of a foil of lesser thickness than five one-thousandths of an inch, it becomes necessary to modify the seam in order to build up the thickness of that part of the torpedo to the minimum thickness of four one-hundredths of an inch as required in the specification. This can readily be done in the manner illustrated, for example, in Figs. 9, 10 and 11, wherein it will be noted that the foil sheet is given a sufficient width in excess of that required to form the basic one-half inch cylinder which embraces the explosive body, to permit of inclusion in the seam and over the entire width of the strap of two extra layers of foil. If with a seam of this formation a foil is used of four one-thousandths of an inch, the effective thickness of the strap motion of the torpedo, consisting in effect of ten layers of this foil, will have an effective thickness of the required four one-hundredths of an inch.

When a foil of thickness less than five one-thousandths of an inch is used, I prefer to provide the torpedo with an outer protective cylinder 10 of tough paper or cardboard as shown in Figs. 9 and 10. This outer cylinder will have imprinted thereon the required warning, and at the strap or bottom side of the torpedo I may utilize this outer cylinder as a medium for including the required coating of sand, in accordance with the specification, the sand, indicated at 12, being attached to the outer cylinder by means of a suitable adhesive. This outer protective cylinder of paper precludes any damage to, or perforation of, the relatively thin lead of the casing. From the embodiment of my invention shown in Figs. 1 to 8, inclusive, it is apparent that I may utilize the outer label in a similar manner to carry the sand at the bottom of the torpedo, it being preferable for this purpose to form the

label of a width corresponding to the length of the explosive-carrying portion of the casing.

It will be apparent from the foregoing description that the invention provides a simple and practical method of forming this desirable type of lead sheathed torpedo so as to meet in full degree the requirements of the standard specifications. It will be understood, of course, that the invention is not limited to a torpedo of the particular cylindrical form shown and described, and that there may be considerable modification as to form without departure from the invention as defined in the appended claims.

I claim:

1. A railway track torpedo comprising a body of explosive composition and a tubular envelope of metal foil, said envelope materially exceeding the explosive body in both the axial and perimetral dimensions, said axial excess providing at each end of said body an extended portion of metal for securing the torpedo to the rail, and the said perimetral excess being folded on itself to provide at one side of the envelope a longitudinal strap of several thicknesses of the foil, said explosive body except in the area of said strap being embraced by a single thickness of the foil, and said thickness being sufficiently small to preclude danger from flying fragments of said foil when the torpedo is exploded, and

said perimetral excess being sufficiently great to afford a strap not materially exceeding 20% of the perimetral dimension of the tube in width and containing at least four thicknesses of the foil.

2. A railway track torpedo comprising a body of explosive composition and a tubular envelope of metal foil, said envelope materially exceeding the explosive body in both the axial and perimetral dimensions, said axial excess providing at each end of said body an extended portion of metal for securing the torpedo to the rail, and the said perimetral excess being folded on itself to provide at one side of the envelope a longitudinal strap of several thicknesses of the foil, said explosive body except in the area of said strap being embraced by a single thickness of the foil, and said thickness being sufficiently small to preclude danger from flying fragments of said foil when the torpedo is exploded, and the said perimetral excess being sufficiently great to afford a strap not materially exceeding 20% of the perimetral dimension of the tube in width and containing at least four thicknesses of the foil, said extended end portions of the envelope being folded longitudinally to afford in those portions additional thicknesses of foil augmenting the thickness of said strap.

GEORGE B. JACKSON.
